UNITED STATES PATENT OFFICE.

JOSEPH W. BIRCH, OF NEW YORK, N. Y., ASSIGNOR OF ONE-HALF TO
STEPHEN T. SMITH, OF SAME PLACE.

DEVICE FOR CUTTING OFF THE FLOW OF GAS TO GAS-BURNERS.

SPECIFICATION forming part of Letters Patent No. 352,391, dated November 9, 1886.

Application filed March 11, 1886. Serial No. 194,865. (No model.)

To all whom it may concern:

Be it known that I, JOSEPH W. BIRCH, a citizen of the United States, residing at New York, in the county and State of New York, 5 have invented new and useful Improvements in Devices for Cutting Off the Supply of Gas to Burners, of which the following is a specification.

This invention has for its object to provide 10 a gas-burner with novel means for automatically closing the supply of gas thereto when the jet has been extinguished without turning a cock to shut off the gas-supply.

The object of my invention I accomplish in 15 the manner and by the means hereinafter described and claimed, reference being made to the accompanying drawings, in which—

Figure 1 is a vertical central section of a burner provided with my cut-off device. Fig. 20 2 is a side elevation thereof with part broken away. Fig. 3 is a vertical section in the plane x x, Fig. 2. Fig. 4 is a central section of a modification thereof on a smaller scale than the preceding figures. Fig. 5 is a side elevation of the same with part broken away.

Similar letters indicate corresponding parts.

In the drawings, the letter A designates a burner which is tapped out at one end so that it can be secured to the gas-pipe, and in its 30 other end is fitted a suitable tip, as usual. Near the lower end of the burner is formed a valve-casing, B, which is divided by a horizontal diaphragm, b, that also closes this end of the burner from communication with the 35 gas in the pipe, and in this diaphragm is a gas-inlet orifice, c, which is controlled by a disk-valve, C, that opens upward and is provided with a suitable seat. The stem c' of the valve extends outward through the casing, and is in 40 connection with a valve-operating device which holds the valve off its seat, so as to allow the gas to enter the burner through the orifice c before and subsequent to ignition, but causes the valve to fall and close upon its seat when 45 the gas-jet is blown out or extinguished in any other manner without shutting off the gas-supply. This valve-operating device is set in motion to effect this result by the expansion of air or by the evaporation of some volatile 50 fluid—such as alcohol—which is confined in a

flask or chamber, D, located in close proximity to the burner and hermetically sealed by a diaphragm, E, which is secured thereto in any suitable manner, and is made of an elastic material, such as rubber. This flask or chamber D is located in a suitable casing, E', that is secured to the burner, and is provided with a neck, e, that closes about the upper end of the tube or chamber, so as to hold the same firmly in an upright position. A button, F, 55 having a flaring head, rests upon the diaphragm, and a bent rod, G, is attached thereto, which is guided and can slide longitudinally in guides f, f' on the casing E. The follower-rod is provided with a trip-pin, g, and a stop, 60 f', at the lower end of the rod prevents the same from being drawn out of its bearings as the diaphragm E is expanded. The valve-rod of the valve C is provided with an extension or valve-rod, I, or it may be simply 70 bent upward; but in either case the rod is provided with a trip-pin, i, that is in a proper position to be engaged by one arm, j, of a lever, j J. The arm J of the lever is hook-shaped, and is provided with a tooth, j', which 75 is engaged by the trip-pin g on the follower-rod G.

The lever J is pivoted at m to the casing E', and in order to throw the former from one position to another in turning on the gas, as will 80 be presently explained, a knob, M, is attached thereto.

The operation of the device is as follows: Suppose that the gas is not ignited, the valve C is down on its seat, and the diaphragm is not 85 distended, all as shown by full lines in Fig. 2, which represents the normal position of the operating parts. To turn on the supply of gas the knob M is turned in the direction of arrow 1, Fig. 2, until the arm J of the lever j 90 J strikes against the trip-pin g, as shown by semi-dotted lines. During this motion of the lever the arm j thereof engages the pin i and carries the valve-rod I upward, consequently the valve C is lifted from its seat and the gas 95 enters the burner and can be ignited. Heat from the flame is transmitted to the contents of the flask or chamber D, whereby the diaphragm is distended and draws up the trip-rod G. The pin g thereof engages with the rod

body of the arm *J* of lever *j* *J*, and forces the latter backward until the rod has been drawn up to such a height that the pin *g* engages with the extreme end of the hook, whence the parts 5 will have assumed the position shown by dotted lines in Fig. 2 and by full lines in Fig. 3, and will remain in this position until the gas is extinguished in some manner—say is blown out. In such a case the contents of the tube 10 or chamber *D* cool and the diaphragm relaxes, which allows the follower-rod gradually to fall, and the pin thereon disengages the arm *J* as soon as it falls below the tooth *j'*. The valve-rod being now free, the valve falls on its seat 15 from gravity and stops the exit of gas.

In the modification shown in Figs. 4 and 5 the valve is subjected to the action of a spring, *N*, which constantly tends to hold the same on its seat, and the button *F* is connected directly 20 to the valve-stem *c* by the valve-rod *I**, so that as the diaphragm is raised or distended the valve is lifted from its seat, and vice versa. To turn on the gas I make use of a cam, *J**, which is pivoted to the casing and which engages with a pin, *i**, on the valve-rod. The cam is turned to lift the valve-rod, and consequently the valve from its seat, by an arm, *O*. The full lines in Fig. 5 show the device in its 25 normal position with the valve down on its seat and the diaphragm or covering not distended. To turn on the gas the cam is moved in the direction of arrow 2 until it assumes the position shown by dotted lines, whereby the valve is lifted from its seat. As the diaphragm 30 or covering is distended the valve-rod *I** is lifted, and in the course of time the pin *i** thereon goes out of contact with the cam, when the same falls back into the position shown by full lines. When the gas is extinguished, the 35 valve is gradually moved to its seat as the contents of the flask or chamber cool and contract. Although this latter device will effectually interrupt the exit of gas, it will not accomplish this result as quickly as the device shown in 40 Figs. 1, 2, and 3, for the reason that in the device shown in Figs. 4 and 5 the closing of the valve takes place with the gradual relaxing of the diaphragm, since the two are rigidly connected with each other, while in the first- 45 described device the valve-rod is not directly connected with the button, and after the jet is extinguished the diaphragm need only relax sufficiently to cause the pin *g* on the fol- 50 lower-rod *G* to clear the tooth on the arm *J*, 55 which distance may be made as minute as desired.

The object of my invention is to provide a device for the purpose designated which will act effectively and quickly, and thus prevent 60 the fatal results frequently occurring from negligence or ignorance.

As the rapidity of action in closing the exit of gas after the flame is extinguished is an essential feature of such devices, I prefer to 65 use alcohol as an agent for expanding the diaphragm, as this liquid will volatilize very rapidly, and vice versa.

Instead of a glass or metal chamber and an attached diaphragm, the entire chamber can be made of some elastic material and fitted 70 into a casing which encompasses it, with the exception of one of its ends, whereby the same result is obtained.

What I claim as new, and desire to secure by Letters Patent, is—

1. The combination, with a burner, of a valve, a closed expansible and contractible chamber having a diaphragm at its upper end and located in close proximity to the burner, a button resting on the diaphragm, and a vertically-slidable rod for connecting the button with the valve, substantially as described. 80

2. The combination, with a gas-burner, of a rising and falling valve having a stem, an expansible and contractible chamber having a diaphragm at its upper end and located in close proximity to the burner, a button resting on the diaphragm, and a rod-connection 85 between the button and the valve, substantially as described. 90

3. The combination, with a gas-burner, of a rising and falling valve, an expansible and contractible chamber having a diaphragm at its upper end and located in close proximity to the burner, a button resting on the dia- 95 phragm, a vertically-sliding rod connected with the button, and means, substantially as described, for connecting the rod with the valve, whereby the rising of the button lifts and opens the valve, substantially as described. 100

4. The combination, with a gas-burner having a valve-chamber, *B*, provided with a horizontal diaphragm, *b*, having an inlet-orifice, *c*, and dividing the chamber, of a valve, *C*, seating on said diaphragm, and having a stem, *c'*, 105 extending to the exterior of the burner, an expansible and contractible chamber, *D*, located in close proximity to the burner, a button, *F*, resting on the upper end of the latter, and a 110 slidable rod-connection between the button and the stem of the valve, substantially as described.

5. The combination, with the burner, of the valve *C*, the valve-rod thereof, the expansible and contractible chamber *D*, located in close 115 proximity to the burner, a follower-rod connected with the upper end of the chamber, and a lever-and-pin connection between the valve-rod and the follower-rod, substantially as described. 120

6. The combination, with a burner, of a valve having a valve-stem, a vertically-slidable rod connected with the valve-stem and having a trip-pin, a turning-lever for acting on said pin to lift said rod, an expansible and contractible chamber having a diaphragm at its upper end and located in close proximity to the burner, and connections, substantially such as described, between the diaphragm and the sliding rod, substantially as described. 125 130

7. The combination, with the burner closed at one end, of the valve-casing *B*, communicating with the burner and the gas-supply pipe, the valve *C* in said casing, the valve-rod

I, having a trip-pin, *i*, the expansible and contractible chamber *D*, located in close proximity to the burner, the follower-rod *G*, carrying a button, *F*, at its upper end, which rests on the chamber, and having the pin *g*, the swinging lever *J*, having the arm *j* and the hook *j'*, and the handle or knob *M*, substantially as described.

8. The combination, with the burner, of the gravitating valve *C*, controlling the gas-supply, the valve-rod *I* thereof, the expansible chamber *D*, located in close proximity to the burner, the follower-rod *G*, in connection with the chamber, the pins *i* and *g* on the valve and follower rods, the pins *i* and *g* on the valve and follower rods, the lever *j* *J*, having a hook-shaped arm engaged by the pin on the follower-rod, and an arm engaging the pin on the valve-rod, substantially as shown and described.

9. The combination, with a burner closed at

one end, of a valve-casing, *B*, communicating 20 with the burner and the gas-supply pipe, of the gravitating valve *C* in said casing, the valve-rod *I* thereof, the casing *E'*, the expansible chamber *D* therein, said casing and chamber located in close proximity to the burner, 25 the button *F*, in connection with the chamber, the follower-rod *G*, the pins *i* and *g* on the valve and follower rods, and the lever *j* *J* engaging the pins *i* and *g*, substantially as shown and described.

In testimony whereof I have hereunto set my hand and seal in the presence of two subscribing witnesses.
